SEAM PRESSING MACHINE

Raymond J. Holmes, Lynn, Mass., assignor to
 Boston Machine Works Company, Lynn,
 Mass., a corporation of Massachusetts

Application February 1, 1932. Serial No. 590,252

14 Claims. (Cl. 69—7)

The present invention relates to seam-pressing machines, and more particularly to that type thereof which is used in the manufacture of men's shoes to press the back seam joining the quarters.

Heretofore this type of machine has been provided with a seam-presser, means for supporting the work, and means for guiding the seam-ridge to a position on the work support beneath the presser. Usually the seam-guiding means comprised a seam-crease guide and a seam-ridge guide formed by two members which embraced the opposite sides of the seam-ridge. Heretofore the seam-ridge and the seam-crease escaped from their guides at points spaced from the seam-presser so that there was a tendency for the seam-ridge to drum head across the space between the work support and the guides and thus resist the efforts of the seam-presser to press the seam-crease into engagement with the work support.

An object of the present invention is to provide a seam-pressing machine in which the seam-presser is relieved of the duty of pressing that portion of the seam-ridge which extends unsupported between the work support and the seam-crease guide into engagement with the work support.

To the accomplishment of this object a feature of the present invention contemplates the provision in a seam-pressing machine having a work support over which is fed work in the form of two pieces sewed together by a seam presenting a seam-ridge on one face of the work and a seam-crease on the other, a seam-presser cooperating with the work support to press the seam, and means for supporting the seam-crease to a point spaced from the work support and the seam-presser and for guiding the opposite sides of the seam-ridge to a point closer to the seam-presser, of means operating upon that portion of the seam-ridge which extends, confined laterally but unsupported from below, from the work support to the seam-crease guide, to depress it into engagement with the work support.

Broadly considered the means for relieving the seam-presser of the duty of depressing the seam-crease into engagement with the work support may take any suitable form found desirable or expedient. But because of the lateral confinement of the seam-ridge at the point of depression, it is preferred to cause the depressing means to preform the seam-ridge and thus prepare the seam-ridge for the operation of the seam-presser. The seam-ridge may be preformed and the seam-

crease set into engagement with the work support by a fin, projecting forwardly from the seam-presser, which, while the seam-crease is unsupported and the opposite faces of the seam-ridge are confined laterally, forms a groove in the end face of the seam-ridge. As the materials on both sides of the groove formed by the fin are confined laterally by the members comprising the seam-ridge guide, the materials are compressed by the act of forming the groove so that when the fin in its feeding movement draws the compressed material out from between the members of the seam-ridge guide, the materials spring outwardly in a convenient position and in the proper direction for the seam-presser to roll them down upon the adjacent faces of the quarters, respectively.

Other features of the present invention reside in certain devices, combinations and arrangements of parts hereinafter described and then pointed out broadly and in detail in the appended claims, possessing advantages readily apparent to those skilled in this art.

The various features of the present invention will be understood readily from an inspection of the accompanying drawing illustrating the best form of the invention at present devised, in which,

Figure 1 is a view in left side elevation of the seam-pressing machine;

Fig. 2 is a detail view in front elevation of the seam-ridge guide and the gage for engaging the free end face of the seam-ridge;

Fig. 3 is a detail view in sectional elevation on the line 3—3, Fig. 2;

Fig. 4 is a detail view in sectional elevation on the line 4—4, Fig. 3;

Fig. 5 is a detail view in left side elevation, the hammer and the seam rubber being in the positions they assume upon their initial engagement with the work;

Fig. 6 is an enlarged detail view in perspective of the hammer;

Fig. 7 is an enlarged detail view in perspective of the gage for engaging the free end face of the seam-ridge;

Fig. 8 is a detail view in perspective of a pair of shoe quarters sewed together, with their grain faces engaged, on a curved line concentric to their edges;

Fig. 9 is a detail view in sectional elevation on the line 9—9, Fig. 5, and

Fig. 10 is a detail view in sectional elevation on the line 10—10, Fig. 5.

The illustrated embodiment of the present invention operates upon a work piece comprising

two quarters 11 and 12 (Fig. 8) which are sewed together by a curved line of stitches 13 concentric to the adjacent edges. If the quarters are leather, the faces engaged in Fig. 8 are grain, the flesh faces being exposed. The quarters are opened up (Fig. 4) to present a seam-ridge 14 on one face of the work and a seam-crease 15 on the other face of the work.

In the machine the work is supported upon a roll 16 for the operation of a seam-presser or hammer 17 and a heated seam-setting or rubbing tool 18 which may have the same relative modes of operation as the corresponding parts disclosed either in the patent to Staples, 1,234,950, July 31, 1917, or the application filed concurrently herewith by Walter P. Osgood. In either event, the hammer 17 operates in a four-motion cycle moving substantially vertically to press the seam-ridge, horizontally to the left (Fig. 1) to feed the work, vertically to leave the work, and horizontally back to the right (Fig. 1) to complete the cycle.

In order to present the seam-ridge properly to the work support 16, the machine is provided with a guide 19 engaged in the seam-crease, a guide 20 embracing the opposite faces of the seam-ridge, and a gage 21 engaging the free end face of the seam-ridge.

The seam-crease guide 19 is secured by a screw 22 to a post carried by the frame of the machine. The free end of the guide 19 terminates close to the work support 16. Near its free end the guide is provided with a horizontal portion 23 having a beveled edge (Fig. 4) for engagement in the seam-crease.

The seam-ridge guide 20 comprises two members 24 and 25 arranged to embrace the opposite sides of the seam-ridge. As shown particularly in Fig. 2 the members 24 and 25 flare inwardly in the direction the work is fed therethrough. The members 24 and 25 are formed on vertical arms of bell-crank levers 26 and 27 (Fig. 4) which are pivoted, respectively, on horizontal pins 28 and 29 which bridge a recess 30 (Fig. 3) formed in a block 31. The bell-crank lever 26 is provided with a recess 32 (Fig. 4) which receives a tooth 33 on the bell-crank lever 27 in order that the spreading movement of the members 24 and 25 under the influence of the seam-ridge may be mutual. The bell-crank levers 26 and 27 are engaged, respectively, by springs 34 and 35, housed in the block 31, in order that the members 24 and 25 may normally have a tendency to assume a closed position. The movement of the members 24 and 25 towards each other is limited adjustably by a cam 36 formed as an eccentric on a stud 37 having a slotted head engaged with one wall of the recess 30 and a threaded shank engaged with the opposite wall of the recess 30. The cam 36 engages the bell-crank lever 26 and is secured in a position to limit the closing movement of the members 24 and 25 by a nut 38 on the threaded shank of the stud 37.

The block 31 is provided with a horizontal way 39 which is engaged by a tenon 40 carried by the lower end of a rod 41 mounted to slide vertically in bearings 42 in a bracket 43 secured to the frame of the machine. The tenon 40 is provided with a horizontally extending slot 44 which embraces the shank of a headed screw 45 threaded into the block 31. With this construction the position of the block 31 with relation to the tenon 40 may be varied to provide for the lateral adjustment of the seam-ridge guide 20.

In order to permit the seam-ridge guide 20 to yield vertically the rod 41 is provided with a col-

lar 46. Coiled about the rod 41 is a spring 47 which is interposed between the upper bearing 42 and the collar 46. The rod 41 near its upper end is provided with a lateral block 48 similar in construction and mode of operation to the corresponding block disclosed in the patent to Staples hereinbefore referred to.

The gage 21 comprises a horizontal part 49 (Fig. 7), provided with a groove 50 on its bottom face to receive the free end face of the seam-ridge, and a vertical part, provided with a vertically extending slot 51 which embraces the shank of a screw 52 in a manner permitting the vertical adjustment of the gage 21 and its retention in the desired adjusted position. The horizontal part 49 of the gage 21 extends parallel and close to the supporting face 23 of the seam-crease guide 19. The gage 21 is prevented from moving laterally relative to the seam-crease guide by the walls of a slot 53, formed in the block 31, which engage the opposite sides of the rectangular head 54 on the vertical part of the gage 21.

After the quarters are opened up the seam-ridge is introduced between the flaring front ends of the members 24 and 25 of the guide 20. These members converge towards each other in the direction the work is fed so that as the seam-ridge moves rearwardly the members 24 and 25 embrace the opposite sides thereof and confine the sides of the seam-ridge to a predetermined path. The members, under the influence of the seam-ridge, move laterally to accommodate themselves to the thickness of the seam-ridge. These lateral movements of the members 24 and 25 are mutual so that the median lines of the seam-ridges inserted successively into the machine are all in the same vertical plane notwithstanding variations in their thicknesses. At the same time the sides of the seam-ridge are engaged by the members 24 and 25, the seam-crease and the end face of the seam-ridge are engaged by the guide 19 and the groove 50 in the gage 21, respectively. The seam-ridge is pushed through the space bounded by the guides 19 and 20 and the gage 21 until the leading end of the seam-ridge projects, unsupported from below, beyond the free end of the seam-crease guide. At this point, a fin 56 projecting forwardly from the hammer 17 into the space between the members 24 and 25 which confine laterally the leading end of the seam-ridge, steps upon the unsupported seam-ridge. The fin 56 has a width narrower than the free end edge face of the unsupported seam-ridge so that when it steps on the unsupported seam-ridge it forms a groove 57 (Fig. 9) in the material forming the free end edge face and displaces the material directly under the groove to set the seam-crease firmly into engagement with the peripheral surface of the work support.

The work-engaging face of the fin 56 is roughened so that when the hammer 17 is moved to the left (Fig. 1) the fin 56 feeds the depressed seam ridge to the left. After the hammer 17 reaches its extreme position of movement to the left in contact with the work, the hammer 17, together with the fin 56, is elevated from the work, returns out of contact with the work to its extreme position to the right (Fig. 1), and is then lowered into engagement with the work. As soon as that portion of the seam-ridge which has been depressed by the fin 56 escapes beyond the ends of the members 24 and 25, the compressed walls of the groove spring outwardly.

Upon the next down stroke of the hammer 17, the fin 56 steps on another portion of the laterally confined but unsupported from below seam-ridge, and the hammer 17 strikes the walls of the groove 57, previously formed by the fin 56, but now unconfined laterally by the seam-ridge guide, and rolls them outwardly into engagement with the adjacent faces of the work pieces, (Fig. 10).

10 The formation of the groove 57 by the fin 56, the rolling of the walls of the groove outwardly by the hammer, and the four-motion feeding movements thereof continue until the seam-ridge passes beyond their influence. In the meantime, 15 the portion of the seam-ridge previously operated upon by the hammer 17 is fed beneath the heated tool 18 which sets the seam in the position to which it has been brought by the hammer 17.

Nothing herein explained is to be interpreted 20 as limiting the various features of the present invention in the scope of its application to use in connection with the particular machine or the particular mode of operation or both selected for purposes of illustration and explanation. While 25 the particulars of construction herein set forth are well suited to one mechanical form of the invention and to the use to which it is put, it is not limited to this use, nor to these details of construction, nor to the conjoint use of all its 30 features, nor is it to be understood that these particulars are essential since they may be modified within the skill of the artisan without departing from the true scope of the actual invention, characterizing features of which are 35 set forth in the following claims by the intentional use of generic terms and expressions inclusive of various modifications.

What is claimed as new, is:

1. In a seam-pressing machine, the combination 40 with a work support over which is fed work in the form of two pieces sewed together by a seam presenting a seam-ridge on one face of the work and a seam-crease on the other face of the work, and a seam-presser cooperating 45 with the work support to press the seam, of means for presenting the pieces to the work support comprising a seam-crease support, a seam-ridge guide and a gage provided with a groove receiving the free end face of the seam-ridge.

50 2. In a seam-pressing machine, the combination with a work support over which is fed work in the form of two pieces sewed together by a seam presenting a seam-ridge on one face of the work and a seam-crease on the other face of the work, and a seam-presser cooperating with the work support to press the seam, of means for presenting the pieces to the work support comprising a support having a longitudinally extending surface engaged in the seam-crease, a 55 seam-ridge guide, and a gage extending longitudinally substantially parallel to the seam-crease supporting surface, engaging the free end face of the seam-ridge.

60 3. In a seam-pressing machine, the combination with a work support over which is fed work in the form of two pieces sewed together by a seam presenting a seam-ridge on one face of the work and a seam-crease on the other face of the work, and a seam-presser cooperating with 65 the work support to press the seam, of means for presenting the pieces to the work support comprising a support having a longitudinally extending surface engaged in the seam-crease, a seam-ridge guide, and a gage extending longitudinally substantially parallel to the seam-

crease supporting surface provided with a groove receiving the free end face of the seam-ridge.

7. In a seam-pressing machine, the combination 80 with a work support over which is fed work in the form of two pieces sewed together by a seam presenting a seam-ridge on one face of the work and a seam-crease on the other face of the work, a seam-presser cooperating with the work support to press the seam, and means for supporting the seam-crease to a point spaced 85 from the work support and the seam-presser and for guiding the opposite sides of the seam ridge beyond that point, of means operating upon that portion of the seam-ridge which extends, confined laterally but unsupported from below, from the 90 work support to the seam-crease guide, to depress it into engagement with the work support.

8. In a seam-pressing machine, the combination 95 with a work support over which is fed work in the form of two pieces sewed together by a seam presenting an upstanding seam-ridge on one face of the work and a seam-crease on the other face of the work, and a seam-presser co-operating with the work support to press the seam, of means movable into and out of engagement with the work during each cycle for pre-forming the material forming the free end edge 100 face of the upstanding seam-ridge for the operation of the seam-presser.

9. In a seam-pressing machine, the combination 105 with a work support over which is fed work in the form of two pieces sewed together by a seam presenting an upstanding seam-ridge on one face of the work and a seam-crease on the other face of the work, of positive means for 110 forming a groove in the material forming the free end edge face of the upstanding seam-ridge.

10. In a seam-pressing machine, the combination 115 with a work support over which is fed work in the form of two pieces sewed together by a seam presenting an upstanding seam-ridge on one face of the work and a seam-crease on the other face of the work, and ambulatory means for forming a groove in the material forming the 120 free end edge face of the upstanding seam-ridge, of means for rolling outwardly the material forming the walls of the groove.

11. In a seam-pressing machine, the combination 125 with a work support over which is fed work in the form of two pieces sewed together by a seam presenting a seam-ridge on one face of the work and a seam-crease on the other face of the work, a seam-ridge guide confining the opposite sides of the seam-ridge laterally, and a 130 seam-crease support terminating above the work support, of means for stepping upon that portion of the seam-ridge confined by the seam-ridge guide which extends unsupported between the work support and the seam-crease support. 135

12. In a seam-pressing machine, the combination 140 with a work support over which is fed work in the form of two pieces sewed together by a seam presenting an upstanding seam-ridge on one face of the work and a seam-crease on the other face of the work, and a seam-ridge guide comprising two members embracing the opposite sides of the 145 upstanding seam-ridge, of a four motion seam-presser having a portion thereof interposed between said members.

13. In a seam-pressing machine, the combination 150 with a work support over which is fed work in the form of two pieces sewed together by a seam presenting a seam-ridge on one face of the work and a seam-crease on the other face of the

5	work and a seam-crease support terminating above the work support, and a seam-ridge guide comprising two members confining the opposite sides of the seam-ridge laterally, of a seam-presser having a part for stepping upon that portion of the laterally confined seam-ridge which extends unsupported between the work support and the seam-crease support, interposed between said members.	80
10	11. In a seam-pressing machine, the combination with a work support over which is fed work in the form of two pieces sewed together by a seam presenting an upstanding seam-ridge on one face of the work and a seam-crease on the other face of the work, a seam-presser cooperating with the work support to press the seam, and means for preforming the seam-ridge for the operation of the seam-presser, of means movable independently of the preforming means for confining the opposite sides of the seam-ridge laterally adjacent the point of operation of the pre-forming means.	85
15	12. In a seam-pressing machine, the combination with a work support over which is fed work in the form of two pieces sewed together by a seam presenting an upstanding seam-ridge on one face of the work and a seam-crease on the other face of the work, a seam-presser cooperating with the work support to press the seam, and means for preforming the seam-ridge for the operation of the seam-presser, of means movable independently of the preforming means for confining the opposite sides of the seam-ridge laterally adjacent the point of operation of the pre-forming means.	90
20	13. In a seam-pressing machine, the combination with a work support over which is fed work in the form of two pieces sewed together by a seam presenting an upstanding seam-ridge on one face of the work and a seam-crease on the other face of the work, a seam-presser cooperating with the work support to press the seam, and means for preforming the seam-ridge for the operation of the seam-presser, of means movable independently of the preforming means for confining the opposite sides of the seam-ridge laterally adjacent the point of operation of the pre-forming means.	95
25	14. In a seam-pressing machine, the combination with a work support over which is fed work in the form of two pieces sewed together by a seam presenting an upstanding seam-ridge on one face of the work and a seam-crease on the other face of the work, a seam-presser cooperating with the work support to press the seam, and means for maintaining the seam-ridge in an upstanding condition with the inside faces of the seam-ridge components pressed together, of means of preforming the free end edge face of the maintained upstanding seam-ridge.	100
